TRANSMISSION SYSTEM FOR STATISTICAL DATA

Arthur H. Dickinson, Bronxville, N. Y., assignor to International Business Machines Corporation, New York, N. Y., a corporation of New York

Application February 3, 1939, Serial No. 254,410

16 Claims. (Cl. 235—61.7)

This invention relates to transmission systems for statistical data and, more particularly, to systems of the type wherein data accumulating and recording units are provided at a secondary station to be operated in accordance with data transmitted from a primary station.

It is the general object of the instant invention to provide novel means for transmitting concurrently a plurality of orders of statistical data to a distant point over a single transmitting medium.

A more specific object of the invention resides in the provision for columnar separation of a plurality of columns of data to be transmitted by assigning a different frequency to each column.

Another object is to provide means for effecting digit separation in accordance with differential time while attaining columnar separation of the data in accordance with different frequencies.

Still another object of the invention is to provide a method for setting up a substantially complex wave comprised of frequencies representative of different columns of statistical and control data, which wave is transmitted and then broken down into its component parts to effect entry into, and operation of, accumulating and recording units of an accounting machine.

A further object is the provision of means whereby different frequencies are used to distinguish one column of data from another irrespective of the differential time at which these columns may be rendered effective.

A still further object resides in the provision of means whereby the substantially complex wave is superimposed on a carrier wave and upon transmission is separated from the latter and further separated into component waves for effecting control of an accounting machine at a distant point.

Another object of the instant invention is to provide means for disestablishing the arrangement and denominational relationship of the original data appearing in a record during the transmitting period and means for reforming the data after transmission for proper control of and entry into a distantly located accounting machine in the same arrangement and denominational relationship as the original data.

It is also within the contemplation of the invention to provide record control of the operations of a distantly located accounting machine in their proper sequence by signals of different frequencies.

It is further contemplated to provide automatic

group control means by which the component parts of a complex wave are compared with control indicia appearing on records to effect control of both transmitting and receiving units in accordance with record groups.

- 5 An additional object resides in the provision whereby like frequencies are established for corresponding columns of records presented successively at a sensing station and automatic group 10 control means compares the time at which like frequencies are established on successive record cards to control accumulating, total taking, and resetting operations of an accounting machine at a distant point.
- 15 In the usual electrical tabulating and accounting machines, the general circuit pattern comprises a single circuit extending to an analyzing unit where the record card, by its passage therethrough and the data indications it bears, causes 20 a number of parallel circuits to be completed to the automatic group control, accumulating, and recording units, the parallel circuits thereupon combining over a single circuit for the return to the source of power supply. According to the 25 present invention, however, a plurality of sources of energy are provided and are combined into a complex wave under record control to be transmitted over a single medium whereupon the original plurality of electrical characteristics are 30 reformed for the control of accumulating and recording units. The fact that a single carrier medium rather than parallel circuits is utilized becomes particularly advantageous where the accumulating and recording units of an accounting 35 machine are remotely located with respect to its record feeding and analyzing unit. It is to be remembered, nevertheless, that the present invention is equally applicable to an accounting machine of the usual structure.
- 40 Other objects of the invention will be pointed out in the following description and claims and illustrated in the accompanying drawings, which disclose, by way of example, the principle of the invention and the best mode, which has been 45 contemplated, of applying that principle.

In the drawings:

Fig. 1 is an outside view of the record feeding and analyzing mechanism showing the card feed and reset clutching devices, which mechanism 50 is located at the transmitting station.

Fig. 1a is a detail section on line 1a—1a of Fig. 1.

Fig. 2 is a detail view of the controlling devices of the accumulator resetting mechanism at the 55 receiving station.

Fig. 3 is a central section of the printing mechanism at the receiver.

Fig. 4 is a detail of an impulse emitting commutator associated with the printing mechanism.

Fig. 5 is a plan sectional view showing the main driving and operating mechanism for the printing unit.

Fig. 6 is a view of one order of the accumulator.

Fig. 7 is a representative diagram of the circuits associated with the transmitter.

Fig. 7a is a diagram of the circuits at the receiver.

Fig. 8 is a timing chart of the circuit closing devices utilized in the circuits at the transmitter.

Fig. 8a is a timing chart of the circuit closing devices employed in the receiver circuits.

The machine to which the features of the present invention are applied is similar to that shown in the U. S. Patent #1,976,617, issued to C. D. Lake and G. F. Daly on October 9, 1934. That patent illustrates and explains in more extensive detail the manner of organization and mode of operation of the various units of a well known type of accounting machine. In the present application, these units will be explained in only as much detail as will be necessary to point out the manner in which the objects of the present invention may be realized.

Before setting forth the general operation of the machine, the various mechanical units will be described and their relationship pointed out thereafter.

Card feeding mechanism

The card feeding mechanism shown in Fig. 1 is identical with that shown and described in the aforementioned patent except that provision is made in the form of a clutching device for interrupting the card feeding operations without stopping the main drive shaft. As described in the said Lake and Daly Patent 1,976,617, the main drive shaft, which is the shaft 13 in the patent, is normally held stationary in a certain angular position, known in the art as the "D" position. Upon energization of a solenoid, it is released and clutched to a constantly running pulley member. Similar arrangements are utilized in accordance with the present invention to start the main drive shafts of the independently located card feeding and manifesting mechanisms from corresponding "D" positions at the same instant, by clutching them simultaneously to two synchronized motor drives, in a manner to be explained.

The analyzing brushes are indicated at UB and LB, and a stack of record cards R are successively advanced by picker 9 to pairs of feed rollers 10 which serve to advance the cards past the upper and lower brushes UB and LB in succession. The shafts upon which rollers 10 are mounted are provided with gears at their extremities, arranged as shown in Fig. 1 for operation by a main driving gear 11 which is freely mounted upon a shaft 8 and which has connection with an arm 15 through a sleeve 7 (Fig. 1a). Arm 15 carries a spring-pressed clutching dog 16 normally held in the position shown by an armature latch 17 which is adapted to be controlled by clutch magnet 18. Between gear 11 and arm 15 are located gear 13 and clutch driving disc 14 freely rotatable upon the sleeve 7. Gear 13 has connection generally designated 12 with main drive shaft 6 which is in operation as long as it is clutched to the main driving pulley, as described in the Lake and Daly Patent 1,976,617. Energization of magnet 18 causes dog 16 to be

tripped into engagement with disc 14, and the card feeding mechanism thereupon causes the records T to be advanced past the brushes UB and LB. Card feeding operations continue as long as magnet 18 remains energized.

During total taking cycles of operation to be explained later, magnet 18 is deenergized and thus card feeding will not take place during such cycles.

10

Printing mechanism

The printing mechanism is shown in Fig. 3 where type bars 20 are carried by cross-head 21 which is slidable vertically on rods 22. Spring-pressed arms 23 pivoted to the cross-head at 24 have their free ends butting the lower extremity of the type bars so that, as the cross-head moves upwardly, the type bars are urged in the same direction. The reciprocating movement of the cross-head is controlled from shaft 19' corresponding to shaft 19 of Fig. 1, the latter being continually driven from the main operating shaft 8 at the transmitter, whenever the main clutch is engaged, and the former being driven from a corresponding shaft (not shown) at the receiver which is kept in synchronism and constant phase relationship to shaft 8 in a manner to be described hereinafter. Shaft 19' has secured thereto a clutch driving element 25 notched to cooperate with a clutching dog 26 carried by and pivoted to listing cam 27. Clutch releasing arm 28 cooperates with dog 26 to hold the parts in the position shown when magnet 29 is deenergized. Energization of magnet 29 causes arm 28 to rock in a counterclockwise direction releasing dog 26 for engagement with element 25 whereupon the listing cam rotates with shaft 19' and, through follower arm 30, effects the rocking of shaft 31.

Secured to shaft 31 are arms 32 whose free ends have link connection to the cross-head 21 causing the latter to be reciprocated once for each revolution of the listing cam. As the type bars move upwardly, the type elements 33 successively pass the printing position opposite platen 34 and ratchet teeth 35 successively pass the toe of the stop pawl 36. Energization of printing magnet 37 effects the tripping of latch 38, permitting stop pawl 36 to engage one of the ratchet teeth 35 and thus positioning the corresponding type element opposite the platen.

Associated with each type bar 20 is a spring-pressed printing hammer 40 pivoted at 41. The hammer normally rests against an operating ball 42 also pivoted at 41, the bail being operatively connected to a tripping member 43 which is biased in a counterclockwise direction by a spring 44. The lower extremity of one arm of member 43 is in latching cooperation with an arm 45 pivoted at 46 to the cross-head operating lever 32. As the lever 32 is rocked in a clockwise direction to elevate the cross-head 21 and the type bar 20, the pivot 46 is moved upwardly therewith and causes the tripping member 43 to be rocked clockwise against the action of spring 44. The connection between the bail 42 and the member 43 is such that the ball is rocked counterclockwise away from the type elements 33. As the lever 32 reaches its utmost extremity of travel, a pin 47 carried by arm 45 brings about the release of the tripping member 43 so that the latter is rocked rapidly in a counterclockwise direction by the action of spring 44. The hammer bail 42 is concurrently rocked in a clockwise direction against the hammers 40 causing the latter to

70

strike the type elements 33 which are in a printing position to effect printing therefrom.

Accumulating mechanism

The adding mechanism is identical to that shown and described in patent referred to and the description thereof will accordingly be limited to a brief explanation of its manner of operation. The accumulator drive shaft 53 (Fig. 6) is geared directly to the main drive shaft at the receiver (not shown) which corresponds to, and is kept in synchronism and constant phase relation with shaft 6 at the transmitter (Fig. 1).

The angular relationship between the teeth on the main clutch ratchets and the armatures of the synchronous motors TM and TM_r is initially established by timing marks on the respective elements. The ratchets have a tooth for each possible angular position at which they may be pulled into synchronous speed. Thus, if the engaging pawls of the clutches are tripped slightly ahead of the tooth in which they are to engage, a slight variance in the tripping time will not cause any detrimental effect in view of the fact that they are engaged at the same instant by the driving faces of the next ratchet teeth. Shaft 53 is thus kept in operation as long as the driving motor at the receiver is clutched thereto and the driving ratio is such that this shaft makes one revolution for each record feeding cycle at the transmitter. A clutch element 54, slidably mounted on shaft 53 but keyed for rotation therewith, is provided for each denominational order of the accumulator. The element 54 is provided with a groove in which fits the short arm of a lever 55 pivoted as shown and having a block 56 normally held as in Fig. 6 by armature latch 51 of an adding magnet 58. A leaf spring 59 bears against the extremity of the longer arm of lever 55 and moves the same in a counterclockwise direction upon release of block 56 by armature 51. This movement brings clutching member 54 into engagement with cooperating teeth 60 which are integral with a gear 61 loosely mounted on shaft 53. Gear 61, when thus coupled to shaft 53, causes the rotation of a gear 62 meshing therewith and consequently the displacement of accumulator index wheel 63. The rearward extremity of member 55 is adapted to be engaged by a finger 64 toward the end of the cycle for the purpose of disengaging the clutch element 54 from teeth 60 and relatching block 56 on armature 51.

Briefly summarizing the adding operation, it is noted that magnet 58 may be energized at various points in the cycle of the machine, depending upon the location of a data indication in a column of the record card being analyzed by the lower brushes LB. This energization may occur in response to a digit indication in any of the index point positions from 9 to 1 inclusive. Should a digit indication be in the "9" index point position, clutch element 54 is tripped nine steps before finger 64 is operated to declutch it. Similarly, a digit indication in the "1" index point position causes the clutch element 54 to be tripped one step before it is declutched by the finger 64. The digit indications are customarily in the form of holes in the card. Each step of clutching arrangement corresponds to a tenth of a revolution in the accumulator index wheel 63 so that a "9" hole moves the wheel $\frac{9}{10}$ of a revolution and a "1" hole moves it $\frac{1}{10}$ of a revolution. Energization of adding magnet 58 also causes the closing of a pair of so-called accumulator-list contacts 58a associated therewith to establish circuits to the

print magnets on listing cycles which will be described later in connection with the circuit diagram.

Read-out mechanism

Also driven by gear 61 is a gear 65. Since the ratio of gears 65 and 62 is 2:1, the former will turn through a half revolution for each revolution of the latter. Carried by and insulated from gear 65 is a pair of electrically connected brushes 66, one of which cooperates successively with the conducting segments 67 while the other cooperates with an arcuate conducting strip 68.

The relationship of the parts is such that, when the index wheel 63 is in its zero position, one of the brushes 66 is in contact with the zero segment 67 and the other brush is in contact with the strip 68, thus forming an electrical connection between the two. If the wheel 63 is displaced to indicate, say, "8," then one of the brushes 66 will be in contact with the "8" segment 67 and the other brush will be in contact with the arcuate strip 68.

The positioning of the brushes 66 provides a convenient electrical read-out mechanism for controlling total printing operation and the electrical circuits involved in these functions will be more fully explained with reference to the circuit diagram.

Accumulator resetting mechanism

The shaft 69 (Fig. 6) upon which the index wheels 63 of an accumulator are loosely mounted is slotted for cooperation with spring-pressed pawls (not shown) pivoted upon and carried by the individual index-wheels in such manner that counterclockwise rotation of shaft 69 causes the index wheels 63 to become engaged and driven forwardly to the zero position during a single revolution of shaft 69.

Referring to Fig. 2, shaft 69 carries a gear 70 at its extremity which is in engagement with gear 71 mounted upon reset shaft 72. Gear 71, of which there is one for each accumulator, is coupled to the resetting shaft 72 in the well known manner more fully explained in the patent above referred to. At the extremity of shaft 72 is a gear 73 (see also Fig. 5) which is adapted to be driven by an intermediate gear 74 which is secured to shaft 75' which corresponds to shaft 75 shown in Fig. 1. Also fixed to shaft 75' is an arm 76' which carries a spring-pressed clutch dog 77' normally held in the position shown in Fig. 2 by a latching arm 78' supported by armature shaft 79' of magnet armature 80'.

Energization of magnet 80' causes dog 77' to be released for engagement with clutch driving element 82'. Element 82' is integral with a gear 83' which meshes with a gear 84', secured upon the shaft 19' which is running constantly as long as the main drive shaft is clutched to the driving pulley. With this arrangement, drive element 82' is in constant rotation and whenever it is desired to effect resetting of the accumulators, magnet 80' is energized to provide a connection between the element 82' and the resetting shaft 72. Resetting is usually an accompaniment of total taking and, by virtue of an intermittent gear connection, occurs during the latter part of a total taking cycle after the totals have been printed.

Although there are no accumulators at the transmitter, a reset clutch is provided as shown in Fig. 1 for operating the P cams which are mounted on shaft 75 and have circuit controlling

contacts associated therewith. This clutch mechanism is similar to that just described for the accumulators at the receiver and corresponding parts at the transmitter are given the same reference characters without the primes. The clutch is engaged during a total taking cycle to cause the P cams to operate their associated contacts to control the machine during a printing cycle at the receiver. It will be noted in the timing chart (Figs. 8 and 8a) that the P and Pr cams are two-cycle cams. This is for the reason that the drive ratio between the cam shaft and the drive shaft is such that these cams make only one revolution for two revolutions of the drive shaft. It is understood that the purpose of such a gear ratio is to provide sufficient time for a total printing cycle to occur. If the printing is accompanied by a resetting operation at the receiver, then both reset clutches function in unison as will be better understood upon explanation of the wiring diagram. It should be mentioned that proper speed and phase relationship of shafts 15 and 15' are maintained, since the drive shafts 19 and 19' at the transmitter and receiver, respectively, are operated in exact speed and phase relationship. The reset magnets 81 and 81' are energized at the same time in the cycle, under control of the related cam contacts, to cause driving engagement of the related clutch mechanisms 71 and 82, and 71' and 82', respectively, at the same time.

Circuit controlling devices

In Fig. 4 is shown a so-called emitter which co-operates with the read-out devices of the accumulator for total printing operations. Carried by a stud 85 coaxially with the shaft 15' is a pair of electrically connected brushes 86, one of which contacts with conducting segments 87 while the other wipes over a common arcuate conducting strip 88. The brushes 86 are carried by a gear 89 driven through an idler 90 from a gear 91 carried by constantly running shaft 19'. The emitter used for controlling total printing operations is timed so that a brush 86 successively contacts with each of the segments 87 as the corresponding type elements 83 of Fig. 3 approach printing position opposite platen 34.

A plurality of cam-controlled contacts, operable only during printing and reset cycles, are provided at the receiver, these contacts being prefixed with the letter "P" but bearing the subscript *r* to distinguish them from the P cams already referred to at the transmitter. The Pr cams are mounted on a shaft 92 driven from shaft 15'. Similar cam controlled devices prefixed with the letter "L" are carried by or may be driven from shaft 19 at the transmitter and shaft 19' at the receiver and these are in constant operation as long as the driving pulleys are clutched to the main drive shafts. The contacts associated with the constantly running cams at the receiver are provided with a subscript *r* to distinguish them from the L-cam contacts at the transmitter.

The usual circuit breakers 133 and 133' are provided at the transmitter and receiver respectively and are timed to make at the beginning of each index point in the machine cycle and break before the end thereof to control circuits to the accumulators and print magnets as will be explained later.

Contacts 150, 152 are operated by the conventional upper and lower card levers which, in turn, are actuated by cards passing the upper and lower sensing stations, respectively. Card lever contacts serve the purpose of preventing initial

operation of the feeding mechanism except upon depression of the start key 129 (Fig. 7). These contacts are instrumental in causing the feeding mechanism to stop at the end of a cycle upon a card feeding failure or when the machine runs out of cards.

All the cam contact devices are indicated in the timing diagrams (Figs. 8, 8a) where their relative timing may be observed.

General explanation of the circuit diagram

The wiring diagram of the electric circuits is shown in Figs. 7 and 7a wherein the various cam contact devices are diagrammatically shown and suitably labeled L, L_r or P, P_r as just explained. The exact timing of these contact devices is shown in Figs. 8, 8a to which reference may be made for the actual time in the cycle of operation during which they function. Due to the presence of numerous interlocking relays in the circuits both at the transmitter and receiver, it has not been advisable in all instances to show relay magnets and their associated contacts in close proximity to one another.

For purposes of clarity in the wiring arrangement the relay contact points are shown in the circuits which they control and their relay magnets are repeated adjacent thereto. Furthermore, the contacts are designated with the same reference numeral as their controlling magnet, followed by a lower case letter.

Synchronizing means.—The driving motors at the transmitter and receiver may be operated in synchronism by any well known means, a preferred method being that illustrated in the U. S. Patent #1,505,158, issued to De Loss K. Martin on August 19, 1924. This method will now be explained briefly in connection with Figs. 7 and 7a and if more detailed description is desired, reference may be made to the above Martin patent. The obvious purpose of maintaining the driving mechanism at each station in synchronism is to assimilate most nearly the condition of an accounting machine having the usual compact structure in which the various units are driven from a common, constantly running drive shaft.

At the transmitter (Fig. 7) a pair of alternators 95 and 96 are provided to supply electrical power at two different frequencies. The frequency set up by alternator 95 becomes the carrier frequency of the system whereas the frequency established by alternator 96 is utilized purely as a synchronizing frequency. Upon the closing of switch S1, a circuit is completed from ground G1, alternator 95, alternator 96, switch S1 now closed, either through filter 98 to ground G2 or via conductor 99 through transmitter 100 to ground G3. Filter 98 is comprised of suitably tuned elements which may be inductance, capacitance, or resistance. Filters are generally classified in the art as high pass, low pass, and band pass filters, filter 98 being of the low pass type and designed to permit the synchronizing frequency but not the carrier frequency to pass therethrough. The synchronizing frequency which appears at the output of the filter is fed to the input of an amplifier 97, then upon closing of switch S2, the output circuit of amplifier 97 affords power supply through switch S2, motor TM, to ground G4. Motor TM is a synchronous motor and is thereby driven at synchronous speed in accordance with the controlling frequency of the alternator 96. It is noted that both the synchronizing frequency and the carrier frequency are impressed upon the transmitter

whose output is in turn impressed upon the aerial and transmitted therefrom as radiant energy in the well known manner.

It will be understood that wherever an amplifier such as 81 is shown hereinafter, the power supply is included in the diagrammatic outline representation of the amplifier and its connected circuits. Furthermore, it will be appreciated that the representative showing includes as many stages of amplification as are necessary to provide sufficient power to operate whatever load may be connected to its output.

When the receiving device 101 receives this radiant energy from the transmitter, it is demodulated and its output circuit includes a signal having a frequency corresponding to the synchronizing frequency mentioned above. Receiver 101 is shown diagrammatically in box form but is understood to include the fundamental sections which comprise the radio frequency amplifier, a detector or demodulator, and an amplifier for the output of the detector, and that such amplification is provided as will be necessary to provide a current of sufficient strength to operate the various relays and magnets of the accumulators and print unit.

In the present system, it will be noted that at the transmitter a current having a given frequency is provided for synchronizing purposes. This current is amplified at the transmitter to drive the motor TM at a fixed speed. The same current is also utilized to modulate the transmitter, from which it is sent to the receiver as radiant energy in the well known manner. The radiant energy is demodulated by the receiver, whose output includes a current having the synchronizing frequency. The latter current is separated from the total output of the receiver and is amplified to drive the motor TM_r at the same fixed speed as TM. It will be seen that in this method of synchronizing the power employed for driving the motors at the transmitter and receiver respectively is supplied locally, and that a current of predetermined frequency is utilized commonly at both transmitter and receiver for controlling the local source of power.

The feed mechanism is driven by motor TM through shaft 6 and accumulators and print mechanism by motor TM_r, through the corresponding shaft of the receiver (not shown) and the shafts 53 and 19', as previously explained. Since motors TM and TM_r are driven at identical speed by current of the same frequency, and since the main drive shafts are clutched to their driving pulleys at the same instant and thus started from the "D" position simultaneously, as previously described, the shafts at the transmitter and at the receiver are driven in a synchronous relationship closely approximating the condition normally attained by actual mechanical connection between these parts in the usual tabulating machine structure.

Columnar frequencies.—In addition to the synchronizing and carrier frequencies already mentioned, a plurality of other frequencies are provided, one for each lower brush position or, in other words, one for each active column of the record card. Twelve such columns are shown in Fig. 7 as indicated by the provision of twelve lower brushes LB and twelve corresponding upper brushes UB. Each of the twelve columns is given a different characteristic frequency to identify it from the others. Any convenient method for providing these frequencies may be employed,

alternators 111 to 122 simply illustrating one such method.

Control frequencies.—In order to control the various operations of the units at the receiver a plurality of control frequencies are set up at the transmitter (Fig. 7) by alternators 125 to 128. The manner in which these frequencies operate will be better understood when the various control circuits are described later herein.

- 10 *Initial reset cycle.*—Slightly above the columnar frequency alternators in Fig. 7 is located the usual group control mechanism generally designated GC, and as is usual in tabulating machines, it is first necessary to set up the group control holding relay magnet R48 before the card feeding mechanism previously described can be set in operation. This is effected by depression of the reset key to close contacts 118, thereby completing a circuit from right side of line 105, contacts 110, relay coil R30, to left hand side of line 106. The lines 105 and 106 are connected through a main switch MS to a suitable source of supply W which provides the electrical energy for energizing the transmitter circuit such as the one just described.
- 15 20 Energization of magnet R30 closes its contacts R30a in the upper part of Fig. 7 which will thereupon complete a circuit from right side of line 105, stop key contacts 107, contacts R30a now closed, main drive clutch magnets 130, to line 106.
- 25 30 Magnets 130, upon becoming energized, cause a coupling of the drive motor to the main drive shaft 6, mentioned above, and, incidentally, also causes the closing of contacts 130a which provide a holding circuit for magnets 130 through 35 cam contacts L1 to line 105. Cam contacts L1 open toward the end of each cycle, and at such time, the circuit is maintained through either contacts UC1c or LC1c which are in series with stop key contacts 107. The manner in which one or more of these contacts in the holding circuit may be opened to interrupt the same will be explained hereinafter.

- 40 45 The relay magnet R30, energized by depression of the reset key, closes a second pair of contact points R30b to complete a circuit from line 105, cam contacts L2, contacts R30b, reset magnet 81, to line 106. As explained in the mechanical description, energization of magnet 81 causes a cycle of operation of the P cam contacts at the transmitter to control various circuits of the system. Contacts P1 (at the lower part of Fig. 7), for example, close to energize the group control relay magnet R48 from line 106, cam contacts P1, relay magnet R48, contacts LCLc or L23, to line 105.
- 50 55 The manner in which the group control mechanism GC functions in the system will be described later.

- 60 65 Prior to the closing of cam contacts P1 to energize magnet R48 in the manner just described, however, relay magnet R49 is energized by a circuit from line 106, relay magnet R49, cam contacts L18, relay contacts R43d, cam contacts P8, to line 106. Contacts R49d close upon energization of magnet R49 to bring alternator 127 into a circuit for transmitting a control signal of a characteristic frequency to the receiver as follows: ground G10, alternator 127, relay contacts R49d now closed, via conductor 109 to transformer 135, filter 136, to transmitter 100 where the frequency created by alternator 127 is superimposed on the carrier wave, then via radio waves to receiver 101 (Fig. 7a), conductor 102, filter 145, transformer 146, via conductor 147 to filter 148, relay magnet 154, to common ground
- 70 75

G13. Contacts 154a close when magnet 154 is energized to complete a circuit for energizing the reset magnet 81' from line 141, reset magnet 81', contacts 154a now closed, cam contacts L2r to line 140. Lines 140 and 141 are connected to a suitable source of supply Wr through the main switch M3r. The energization of magnet 81' causes the resetting of the accumulators, to clear out any old amounts which may be standing therein and prepare the accumulators for new entries. The main clutch 138', of course, must be energized to drive the adding wheels through the reset just described. Referring to the lower part of Fig. 7, contacts 138b close upon energization of the main clutch 138, so that alternator 128 supplies power at a characteristic frequency to the receiver over a circuit similar to that previously traced via conductor 141 (Fig. 7a) to filter 148, relay magnet 153, to ground G13. Relay contacts 153a close to energize the main clutch 138'. Briefly, then, upon depression of the reset key both main clutches and both reset magnets are energized concurrently to cause the operation of the P cams at the transmitter and the operation of the P_r cams and the reset of the accumulators at the receiver. Immediately following the reset cycle, the feeding of record cards may be initiated upon depression of the start key.

Starting circuit.—With relay magnet R43 energized and the accumulators cleared, depression of the start key to close contacts 129 completes a circuit from line 105, conductor 123, contacts 129, relay magnet R43, relay contacts R49b, relay magnet R32 to line 113. The contacts R49b will be in their normal deenergized position because when magnet R43 is energized, the circuit to magnet R49 is broken. Relay contacts R33a are in parallel with the previously mentioned contacts R38a and complete the following circuit through the main clutch magnet 138: from line 105, stop key contacts 107, relay contacts R38a now closed, main clutch magnet 138, to line 106. The energization of magnet 138 is again accompanied by the energization of the main clutch magnet 138' at the receiver by means of the previously described circuit energized from alternator 128. Thus, the main drive shafts of the transmitter and the receiver start and continue to run at identical speed and phase relation.

Relay magnet R32 is provided with a pair of contacts R32a which are adapted upon closure to complete a circuit to the card feed control relay magnet R38. This circuit is traceable from line 106, relay magnet R38, contacts R32a now closed, stop key contacts 107a (operable concurrently with the contacts 107), contacts R43c of the group control relay magnet R43 which are now closed, cam contacts P8, to line 105. This circuit, it will be observed, can only be completed when the group control relay magnet 43 is energized. Magnet R38 closes its contact points R38b which are wired in series with card feed clutch magnet 18 to energize the latter so that records commence to feed. Contacts R38a also close to provide a holding circuit for magnet R38 through lower card lever relay contacts LCLb which close as the first record card reaches the lower brushes.

Card lever circuits.—As the record cards are advanced past the upper set of analyzing brushes UB, the usual upper card lever contacts 150 are closed to complete a circuit from line 105, contacts 150, magnet UCL, to line 106. Magnet UCL controls a number of contacts which are disposed

in various circuits for controlling purposes. One of these contacts, for example UCL₆ pointed out above as being in the holding circuit for the main clutch 138, helps interrupt this circuit if cards fail to feed past the upper brushes. De-energization of main clutch 138 is always accompanied by deenergization of main clutch 138' at the receiver, because contacts 138b (Fig. 7) open to break the previously described control circuit to the receiver from alternator 128, with the result that the main drive shafts are simultaneously latched up in the "D" position, in the well known manner. Since the card lever contacts 150 open between successive cards, a holding circuit is provided through contacts UCL₄ and cam contacts L8 which serve to maintain magnet UCL energized during the interval when contacts 150 are open. In a similar manner, the lower card lever relay contacts 152 cause energization of lower card lever relay LCL and the contact points LCL₄ cooperate with cam contacts L8 to provide a similar holding circuit.

Listing circuits.—The circuit for the listing magnet 28 (Fig. 7a) is completed from line 140, cam contacts L2r, cam contacts P10r, TAB-LIST switch set to the list position, upper and center straps of relay contacts G1c, listing magnet 28, to line 141. Through this circuit magnet 28 is energized during each cycle of operation of the machine and the printing mechanism will function accordingly.

As the record cards advance past the lower brushes LB at the transmitter, circuits are provided for communicating the descriptive data analyzed by these brushes through accumulator list contacts 58a to the printing magnets 37 at the receiver which control the stopping of the type bars as already explained in operation of the printing mechanism given hereinbefore. The list contacts 58a are closed upon energization of the adding magnets as the latter receive impulses from the analyzing brushes LB at the transmitter. The adding circuit will be explained later. The closing of a pair of accumulator list contacts 58a completes a circuit to a print magnet 37 as follows: from line 140, circuit breaker contacts 133' now closed, the particular contacts 58a which are also now closed, the print magnet 37 in series therewith, LIST-TAB switch set to LIST, to line 141. Print magnet 37 upon energization stops the upward movement of the type bar it controls to effect the listing of the digit analyzed on the record card at the transmitter.

Adding circuits.—The circuits for adding into the accumulators are completed simultaneously with the listing circuits just described when all the list control switches are set for listing. When the switches are set to the other position, no listing occurs but adding into the accumulator takes place as data entries are read from each card passing the lower brushes LB. A representative adding circuit is traceable from alternator 122, jack 132, plug wire to jack 134, brush LB through the hole in the card in the corresponding column, contact roll 143, relay contacts LCL₄ now closed, circuit breakers 133, transformer 137, via conductor 109 to transformer 138, filter 138, transmitter 108, receiver 101, conductor 102, filter 145, transformer 146, filter 158 which passes this particular columnar frequency, adding magnet 58 for this column to common ground G12. The circuit just traced energizes the adding magnet 58 for one order of 75 the accumulator to turn its adding wheel in a

manner previously described to effect addition.

Group control.—When the group control switch 160 (Fig. 7) is set to the "on" position, cards are allowed to continue to feed as long as the control indicia on successive cards passing the upper and lower brushes remain the same. The principle is the same as that shown in Patent #1,976,617 previously referred to. A representative control circuit is from alternator 111, jack 132, plug wire to jack 134, lower brush LB, through hole in the card in the corresponding column, contact roll 143, contacts LCL_f now closed, circuit breaker contacts 133 also now closed, transformer 137, filter 138 which passes this particular columnar frequency, control magnet 171 in series therewith, jack 165, plug wire to jack 166, upper brush UB in the corresponding column, through hole in this column of the card at the upper brush, contact roll 142, cam contacts L11, cam contacts L12 now closed, to ground G14. It will be noted that the circuit just traced depends upon the fact that the hole in the record card at the upper and lower brushes is the same in the particular column on which the control is operating. Energization of the particular magnet 171 by the circuit just traced causes the closing of its 171a contact points which are in series with one of the control magnets 172 and provide a circuit to energize the latter from line 106, magnet 172, contacts 171a, common conductor 170 to line 105. Contacts 172a close when magnet 172 becomes energized to provide a holding circuit through cam contacts L28, and contacts 172b also close to complete a circuit for maintaining the group control relay magnet R43 energized. The latter circuit is traceable from line 106, relay contacts R43a, relay magnet R43, conductor 169, contacts 172b now closed, jack 175, plug wire to jack 176, through left and center strap of contacts UCLc now closed, to line 105. This circuit is not set up upon the occurrence of a group change and the relay magnet R43 is deenergized on the next cycle when L23 breaks, the card feeding mechanism continuing under its momentum to the end of the cycle where it is latched up by the card feed clutch 17. The operations just described are well known in the tabulating art and are described in detail in the previously mentioned Patent #1,976,617.

Total printing and reset cycle

After the opening of relay contacts R43c (Fig. 7) upon the occurrence of a group control change, relay contacts R43d close to complete a circuit from line 106, relay magnet R49, cam contacts L19, contacts R43d now closed, cam contacts P9, to line 105. Energization of relay magnet R49 closes its contact points R49a which are in series with the reset clutch magnet 81. The circuit which energizes magnet 81 is traceable from line 106, magnet 81, relay contacts R49a now closed, cam contacts L2 to line 105. Relay contacts 49d also close to render alternator 128 effective to energize the circuit for operating reset clutch magnet 81' at the receiver concurrently with the energization of magnet 81 at the transmitter in a manner already described under the heading of "Initial reset cycle." Upon energization of the reset magnets 81 and 81' the P and Pr cams start to turn and the first operation to take place is the printing of the totals standing in the accumulators at the receiver. This is brought about as follows: at the start of the cycle a circuit is completed from line 106, 75

relay contacts R43b, relay contacts R43c now closed, contacts LCLg now closed since there is a card at the lower brushes, relay magnet 200, cam contacts L18, to line 105. Energization of relay magnet 200 causes its contact points 200a to close, thereby to complete a circuit to the receiver from ground G11, alternator 128, cam contacts L24 now closed, contacts 200a, conductor 169, transformer 135, filter 136, transmitter 168, receiver 161, conductor 162, filter 145, transformer 146, conductor 147, filter 138 adapted to pass this particular control frequency, relay magnet 188, to common ground G18. Energization of magnet 188 by the circuit just traced completes an obvious circuit for energizing total print control magnets 191, 192 which are then maintained energized through contacts 192e and cam contacts L18r. Contacts 191a-d and 192a-d connect the readout mechanism of the accumulators with the print magnets 87, the latter becoming energized at differential times under the control of the total print emitter as its brushes 86 sweep the segments 87, in a manner already described, to stop the type bars in accordance with the totals standing in the accumulators and thus effect printing of these totals.

The total printing operation is followed by a resetting of the accumulators to clear the same in preparation for new entries to be made therein from the following group of record cards. This is so well known in the art that further description here is deemed unnecessary.

Automatic resumption of card feeding

35 Cam contacts L3 are provided to energize the start relay magnet R32 near the end of the resetting cycle of operations to pick up and energize the card feed clutch magnet 18. The circuits involved in the starting of the machine have been 40 already traced in detail and the operations controlled thereby will proceed in the same manner as above.

Group indication cycle.—On the first tabulating cycle after a reset, if certain machine 45 switches are properly thrown, a group indication is effected in the following manner: the GI magnet (Fig. 7) is energized by a circuit from line 106, relay magnet GI, contacts 201b, contacts L25, switch 180 in the position shown for group 50 indication, lower card lever contacts 182, to line 105. Relay magnet GI is held energized through its contacts GIa and cam contacts L7. Shortly after the energization of magnet GI, cam contacts L26 make (see timing chart Fig. 8) to complete a circuit for energizing the control magnet 201. The circuit is traceable from line 106, magnet 201, contacts L26, now closed, switch 181 in the position shown for group indication, contacts GIc now closed, contacts GIa also now closed, cam contacts L7, to line 105. Magnet 201 is maintained energized through its contact points 201a which now close and cam contacts P11. Energization of magnet 201 causes normally closed contacts 201b to open in order to 60 prevent the energization of magnet GI on subsequent tabulating cycles prior to the next group change.

Magnet GI, when energized, causes contacts G1b to close and a circuit is completed when contacts L27 close from alternator 128, contacts L27, contacts G1b, conductor 169, transformer 135, filter 136, transmitter 168, receiver 161, conductor 162, filter 145, transformer 146, conductor 147, filter 138, relay magnet 152, to common ground G18. Energization of magnet 152

closes its contacts 152a to complete an obvious circuit for energizing the group indication relay magnet GI' at the receiver. Contacts GI'a close to provide a holding circuit for magnet GI' through cam contacts L1r. Contacts GI'b also close and the circuit which was traced previously to the magnet 152 branches through these contacts, through filter 159 which passes this columnar frequency through the print magnet 31 in series with filter 158 to common ground G13. Energization of print magnet 31 effects the usual group indication, this circuit being completed only on the first card cycle after a reset because of the fact that magnet GI at the transmitter is deenergized when L1 breaks and contacts GIb open to cut off the source of energy, namely, alternator 125.

It is understood that the list clutch magnet 29 is energized for this cycle to set the printing mechanism in operation to print the group indication just referred to. The specific circuit is traceable from line 141, list clutch magnet 28, center and lower strap of contacts GI'c now closed, cam contacts P10r, cam contacts L2r, to line 140.

Summary of operation

Each signal passed to the transmitter has both primary and secondary distinguishing characteristics: the former being constant and serving to segregate the signal in the correct channel of the receiving station and thereby to restore the position of the character in relation to the other characters, the latter being variable to represent the signification of the character and being translated by suitable manifesting means into the particular character which it represents.

It has been described how a single control frequency and a single columnar frequency control the accounting machine at the secondary station. It has also been set forth above how a single column group control frequency is effective not only to control operations at the transmitter but also at the receiver. It will be appreciated that, in the operation of this system, more than one control frequency and more than one columnar frequency may occur simultaneously. It will be further appreciated that more than one group control frequency may occur simultaneously. The columnar frequencies occur simultaneously when more than one column of the record card contains statistical data appearing at the same differential time and more than one control frequency occurs simultaneously when at least two transmitter control circuits are effective. Such control and columnar frequencies combine to form a complex wave for modulation of the transmitter carrier.

At the receiver demodulation of the carrier takes place and the remaining complex wave is fed to a filter system. In this system the complex wave is broken down into its component frequencies, each individual filter passing a single frequency. Thus, if two control frequencies occur simultaneously, two control filters pass differing frequencies simultaneously, which are effective in separate related circuits. Similarly, if two columnar frequencies occur simultaneously, two columnar filters pass differing frequencies which are effective to operate, for example, two or more accumulator columns or two or more print magnets simultaneously.

It is understood that the group control frequencies are not transmitted to the receiver. There is, however, at the transmitter a combi-

nation of these frequencies into a complex wave and a separation into their component frequencies by a filter system. Thus, if control data in two columns of a record appears simultaneously, two filters of this system pass differing frequencies simultaneously, and currents at such frequencies are effective to operate the group control circuits of the machine as described above under the heading of "Group control." From the foregoing, it is seen that machine routine control, group control, and data representing frequencies are combined into a complex frequency wave for transmission over a single medium which may be either the carrier of a radio system or a wire. Upon reception at a distant point, as has been pointed out, the complex wave is broken down into its component frequencies for machine control and accumulating or recording mechanism control. It is to be remembered that the number of frequencies which are transmitted and broken down at any index point position may vary, such variation being in accordance with the number of control circuits effective at a particular time or the number of data columns in the record which are punched with the same digit indications.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a remotely controlled accounting machine system, cyclically operated means to feed records in succession to an analyzing section of the system, means at that section to analyze corresponding columns of successive records simultaneously for control designations therein during a cycle of the feeding means, stop means normally capable of stopping the feeding means at the end of the cycle, a plurality of sources of current of different frequencies, one for each column of the record, a plurality of external circuits associated with the different frequency sources, a single carrier having common connection with said circuits, the analysis of a control representation in one of the columns of a record at the analyzing section by the analyzing means serving to complete a related one of said external circuits to cause flow of current of predetermined frequency from the associated frequency source to the carrier and means responsive to the current of the frequencies set up on the carrier by the control representations and adapted to be rendered effective only upon agreement in location of a control representation in the corresponding column of the other record at the analyzing section to cause continuance of operation of the record feeding means into the next cycle by rendering the stop means ineffective.

2. In a remotely controlled accounting machine system, cyclically operated means to feed record cards successively to an analyzing station, means at said station comprising two sets of analyzing brushes adapted to analyze successive cards simultaneously for control indicia in corresponding columns thereof during a cycle of the feeding means, stop means normally capable of stopping the feeding means at the end

of a cycle, a plurality of sources of current of different frequencies, one for each column of the card, means effective upon analysis of the control indicia in the card by one set of brushes for causing the related sources of current to emit signal waves of different frequencies to represent said card columns and to impress said signal waves on a single carrier so as to form a complex wave, a plurality of control circuits associated with the other set of brushes, means responsive to the currents of the frequencies set up on the carrier by the control indicia capable of setting up currents of corresponding frequencies in the control circuits including filtering means for causing each of said control circuits to be selected for operation only upon reception of its corresponding frequency, and means under control of the last mentioned set of brushes in accordance with the identity in location of the control indicia in corresponding columns of the card being analyzed by the latter set of brushes to cause operation of the selected control circuits to render the stop means ineffective.

3. In a system for concurrently manifesting a plurality of characters in definite relative positions, means for generating a number of constantly differentiated signals, one for each of said positions, control means operatively associated with said signal generating means and adapted to impart to the individual signals secondary distinguishing characteristics representative of the significations of the characters in the positions to which they respectively appertain, transmitting means controlled by said control means so as to impress upon a single medium of transmission signals reproducing the constant differentiation and secondary distinguishing characteristics of the signals from said control means, means to receive the signals from said single medium of transmission, means operatively connected to said receiving means for segregating the signals received thereby, according to their constant differentiation, and manifesting means comprising a plurality of units operatively associated with said segregating means so as to be individually controlled by the respective segregated signals, the units of said manifesting means being differentially responsive to the signals in dependence upon the secondary distinguishing characteristics thereof, to manifest the characters represented thereby.

4. In a system for concurrently manifesting a plurality of characters in definite relative positions, transmitting means and receiving means interconnected by a single medium of transmission, means for generating a number of constantly differentiated signals, one for each of said positions, control means adapted to pass the signals individually to said transmitting means at differential times to represent different characters, said transmitting means being responsive to said signals to transmit to said receiving means signals reproducing the constant differentiation and differential timing of the signals passed by said control means, means operatively connected to said receiving means for segregating the signals received thereby, according to their constant differentiation, and manifesting means comprising a plurality of units operatively associated with said segregating means so as to be individually controlled by the respective segregated signals, the units of said manifesting means being differentially responsive to the signals in dependence upon the differential timing thereof, to manifest the characters represented thereby.

5. In a system for concurrently manifesting a plurality of characters in definite relative positions, transmitting means and receiving means interconnected by a single medium of transmission, means for generating a number of signals, one for each of said positions, the signals being constantly differentiated by different frequencies to identify each with a particular one of said positions, control means adapted to pass the signals individually to said transmitting means at differential times to represent different characters, said transmitting means being responsive to said signals to transmit to said receiving means signals reproducing the frequencies and differential timing of the signals passed by said control means, means operatively connected to said receiving means for segregating the signals received thereby, according to their frequencies, and manifesting means comprising a plurality of units operatively associated with said segregating means so as to be individually controlled by the respective segregated signals, the units of said manifesting means being differentially responsive to the signals in dependence upon the differential timing thereof, to manifest the characters represented thereby.

6. In a system for manifesting data from a record sheet whereon indicia appear in a plurality of columns and identify characters individually by their locations in particular index point positions in the columns, means to feed the record sheet in the direction of its columns, analyzing means comprising sensing devices assigned to different columns to analyze the columns simultaneously as the record sheet is fed, means for generating a plurality of constantly differentiated signals and conducting said signals to the respective sensing devices of said analyzing means, transmitting means and receiving means interconnected by a single medium of transmission, means to convey signals passing through said analyzing means as indicia are sensed, to said transmitting means for transmission to said receiving means, the signals being differentially timed in accordance with the index point positions of the indicia, means operatively connected to said receiving means for segregating the signals received thereby, according to their constant differentiation, and manifesting means comprising a plurality of units operatively associated with said segregating means so as to be individually controlled by the respective segregated signals, the units of said manifesting means being differentially responsive to the signals in dependence upon the differential timing thereof, to manifest the characters represented thereby.

7. In a system for manifesting a plurality of multi-order items of data composed of characters which vary in the individual orders, transmitting means and receiving means interconnected by a single medium of transmission, means for energizing said transmitting means for each item to transmit through said medium wave groups of different frequencies pertaining to the respective orders of the data, means controlling the operation of said energizing means so as to impart to the wave group of each frequency secondary distinguishing characteristics representative of the character in the order to which it appertains, means connected to said receiving means for segregating the wave groups of different frequencies in different channels, and multi-order manifesting means comprising individual control means for its different orders operatively associated with the respective channels of said

segregating means, said control means being adapted to respond to said wave groups differentially in each order in dependence upon the secondary distinguishing characteristics of the wave group, to cause the related order of said manifesting means to manifest the character represented by said secondary distinguishing characteristics.

8. In a system for manifesting multi-order data composed of characters which vary in the individual orders, transmitting means and receiving means interconnected by a single medium of transmission, means for energizing said transmitting means to transmit through said medium wave groups of different frequencies pertaining to the respective orders of the data, cyclically operating means controlling the operation of said energizing means, adapted to determine independently for each order the fraction of each cycle during which a wave group of the frequency pertaining to the respective order is transmitted, to represent particular characters; means connected to said receiving means adapted to segregate the wave groups of different frequencies in different channels, multi-order manifesting means comprising individual control means for its different orders operatively associated with the respective channels of said segregating means, said control means being adapted to respond to said wave groups differentially in each order, according to the intra-cyclical timing of each wave group, to cause the related order of said manifesting means to manifest the character represented by the fraction of the cycle during which the particular signal was transmitted.

9. In a system for manifesting multi-order data represented by sensible indicia on a record sheet, the indicia representing different characters by their placement at different index point positions in the columns pertaining to their respective orders, transmitting means and receiving means interconnected by a single medium of transmission, means associated with said transmitting means for feeding the record sheet in the direction of its columns at a constant rate, analyzing means connected with said transmitting means, comprising devices for sensing the individual columns of the record sheet, a plurality of sources for generating signal waves of different frequencies, and means for connecting said sources individually to the respective sensing devices of said analyzing means, whereby said transmitting means is energized to transmit through said medium signal waves identified with the respective columns of the record sheet by their frequency and secondarily differentiated by their differential timing to represent different characters; means connected to said receiving means for segregating said signal waves in different channels, according to their frequencies, manifesting means comprising a plurality of manifesting elements representing different orders of the data to be manifested, driving means for said manifesting means operating in synchronism with said record sheet feeding means and having means for imparting differential movements to said manifesting elements, and control means operatively associated with the respective channels of said segregating means, adapted to determine the extents of the differential movements of the different manifesting elements, in dependence upon the differential times of the respective signal waves, to determine the characters to be manifested.

10. In a system for manifesting multi-order

data represented by sensible indicia on a record sheet, the indicia representing different characters by their placement at different index point positions in the columns pertaining to their respective orders; transmitting means and receiving means interconnected by a single medium of electrical transmission, means associated with said transmitting means for feeding the record sheet in the direction of its columns at a constant rate, analyzing means electrically connected with said transmission means, comprising devices for sensing the individual columns of the record sheet, a plurality of sources of alternating current of different frequencies and means for connecting said sources individually to the respective sensing devices of said analyzing means, whereby said transmitting means is energized to transmit through said medium signals identified with the respective columns of the record sheet by their frequency and secondarily differentiated by their differential timing to represent different characters; means connected to said receiving means for segregating said signals according to their frequencies in different circuits, manifesting means comprising a plurality of manifesting elements representing different orders of the data to be manifested, driving means for said manifesting means operating in synchronism with said record sheet feeding means and having means for imparting differential movements to said manifesting elements, and control means operatively associated with the respective circuits of said segregating means, adapted to determine the extents of the differential movements of the different manifesting elements, in dependence upon the differential times of the respective signal waves, to determine the characters to be manifested.

11. In a system for manifesting multi-order data composed of characters which vary in the individual orders, transmitting means and receiving means interconnected by a single medium of transmission, a plurality of parallel channels each including a source for generating a signal wave of a particular frequency to identify a particular order of the data, said parallel channels being joined by a common channel to said transmitting means, means controlling said parallel channels individually to release therethrough signal waves of the respective frequencies, differentially timed to represent the characters in the respective orders of the data, whereby discrete or complex waves are set up in said common channel for transmission by said transmitting means; means connected to said receiving means for segregating the signal waves in different channels, according to their frequencies, and multi-order manifesting means comprising individual control means for its different orders operatively associated with the respective channels of said segregating means, said control means being adapted to respond to said signal waves differentially in each order in dependence upon the differential timing of the signal wave, to determine the character to be manifested.

12. A system as described in claim 11, wherein the signal waves of different frequencies set up in said common channel are discrete or complex depending upon whether the characters they represent are different or identical.

13. In a system for manifesting at a remote point multi-order data represented by sensible indicia on a record sheet, transmitting means and receiving means interconnected by a single medium of transmission, a main source of elec-

trical energy supplying power to said transmitting means at two different frequencies, one adapted to be a carrier frequency and the other a synchronizing frequency, means including a synchronous motor drive for feeding the record sheet, means for supplying electrical energy of synchronizing frequency from said main source to said synchronous motor drive, means for impressing upon the carrier frequency energy issuing from said transmitting means, modulating waves of different frequencies identified with the respective columns of the record sheet, each of the modulating waves being secondarily differentiated to represent the characters in the respective columns of the record sheet; manifesting means comprising a plurality of manifesting elements representing different orders of the data to be manifested, driving means for said manifesting means including a synchronous motor and means operated by said last motor for imparting differential movements to said manifesting elements, means electrically connected with said receiving means for segregating the synchronizing frequency from the other frequencies, means for amplifying the current of said synchronizing frequency and supplying the amplified current to said last mentioned synchronous motor, to synchronize the drive of said manifesting means with that of said record feeding means, means electrically connected with said receiving means for separating the modulating waves from the carrier waves and segregating the modulating waves in individual parallel circuits according to their respective frequencies, and control means operatively associated with the respective circuits of said segregating means, adapted to determine the extents of the differential movements of the different manifesting elements, in dependence upon the differential times of the respective signal waves, to determine the characters to be manifested.

14. The method of manifesting characters by groups at a remote receiving station, which comprises generating different signals for the different characters of a group, which are constantly

5 differentiated to identify each with a character in a particular position in the group, and which are individually variably distinguished by secondary distinguishing characteristics representative of the significations of their related characters; impressing said signals upon a single medium of transmission; receiving said signals from said medium of transmission at the receiving station and segregating them according to their constant differentiation; and manifesting the characters represented by the secondary distinguishing characteristics of the segregated signals.

15. The method of manifesting a group of characters in a brief period of time, at a remote receiving station; which comprises generating, in a single medium of transmission, signal waves which have different frequencies identifying them respectively with the different characters of the group, and which are individually differentially timed within said period of time to represent the significations of their respective characters; receiving the signal waves from said medium of transmission at the receiving station and segregating them according to their respective frequencies; and manifesting the characters represented by the differential times of the individual segregated signals.

16. The method of manifesting a group of characters in a brief period of time at a remote receiving station; which comprises electrically generating signal waves of different unvarying frequencies for the respective characters, during particular fractions of the period of time, representative of the significations of the respective characters; transmitting said signal waves through a single medium of transmission in which any contemporaneous signal waves are merged into a complex wave; receiving the signal waves at the receiving station and segregating them according to their respective frequencies; and manifesting the characters represented by the differential times of the individual segregated signal waves.

ARTHUR H. DICKINSON.
